ADAPTABLE ELECTRIC HAND TOOL

Harry A. Ungar, Los Angeles, Calif.

Application June 26, 1935, Serial No. 28,534

3 Claims. (Cl. 219—21)

This invention is an electric hand tool of the type embodying a soldering-iron element.

An object of the invention is to provide a tool of this class with means to greatly increase its utility by the ready interchange of various tip elements for performing several different functions as met in divers arts and professions as later disclosed herein.

A further object is to provide an implement of this type of rugged and substantial structure, and at the same time of low cost and of a highly practical combination.

The invention consists of certain advancements in this art as set forth in the ensuing disclosure and having, with the above, additional objects and advantages as hereinafter developed, and whose construction, combinations and details of means, and the manner of operation and the mode of manufacture will be made manifest in the description of the herewith illustrative embodiment; it being understood that modifications, variations and adaptations may be resorted to within the scope, principle and spirit of the invention as it is more directly claimed hereinbelow. It is understood that the functional use of the apparatus of this disclosure in any other art than that herein set forth is deemed to be within the adaptation of the invention.

Figure 1 is a side elevation, slightly broken away, of the tool as adapted for hot point scrib- 30 ing. Figure 2 is a perspective of a flexible blade element applicable to the tool. Figure 3 is a perspective of a dental-wax applying element for the tool. Figure 4 is a side elevation of an adaptable element for soldering. Figure 5 is a sectional, side elevation of the handle of the tool, and Figure 6 is an end view thereof. Figure 7 is a side elevation of the heating unit assembly of the tool. Figure 8 is a side elevation of the unit muzzle, and Figure 9 is an end view thereof.

Figure 10 is a side elevation of the high voltage, heating coil, filament, and Figure 11 is an enlarged detail view of a step in its manufacture. Figure 12 is sectional detail of a low voltage heating coil.

The tool includes a hard, di-electric, tubular handle 2 of hollow conical form diverging from its remote end toward a transverse, peripheral flange 3 on its larger end and which flange serves as a means to elevate its end of the handle from a plane support on which it may rest and as a heat barrier to protect the fingers of the user of the tool who grasps the handle just back of the guard flange 3. As a further protection against such heat as may be conducted back by the han-

dle 2 this is provided with a cushion sleeve 4, preferably of cork or cork composition, snugly fitting the large end of the handle.

Extending into the handle is an electric service cord 5 whose wires 6—7 are knotted at 8 and pulled back and jammed tightly in the bore of the handle so that any twisting effort formed in the extension cord during its use will not be transmitted to parts attached to the ends of the wires in the handle; that is to the heating unit 10 assembly of the tool.

The assembly, as shown in Fig. 7, includes a ceramic bushing 10 with a reduced end 11 adapted to be pushed into and cemented in the flanged end of the handle 2 and fixed therein by a key, 15 of any suitably type, 12. A feature of the assembly resides in means for providing for adaptation of one or another of various working elements of which a set is provided with the present device, and providing for use of the tool as a burning scribe without attachment of an extra piece or 20 working element.

Extending through the bushing 10 is a small, ceramic tube 13, Fig. 10, through which extends a small ribbon-wire conductor 14. A highly effective method of making up the heating coil 25 unit of the tool resides in wrapping a fine, filament wire 15 about the extended end 14a of the ribbon 14, Fig. 11, and then bending the end 14a back over the end of the tube 13 and then making 30 a few turns of the filament 15 on the lapped end to tie it down on the tube. Then the filament is coiled at 15a to form the hot zone of the unit (when energized) and from this coil the filament is wide-space coiled at 15b back toward the opposite end of the tube 13, stopping at about its 35 mid-length where it is wrapped at 15c on a lap of ribbon wire 16 on the tube.

All of the coiled filament 15 is now coated with a plastic, cement insulator 17, Fig. 7, and when the coat has set, or before if preferred, it is passed into the bore of the tube and cemented in position so that the hot zone coils 15a will project enough to receive a metal muzzle 18 which telescopes over the insulated filament 15; the muzzle being worked into the outer end of the bushing 10 at the same time that the filament and its core tube is being inserted and cemented in the bushing. When the heater assembly has set one ribbon wire, as 16, is electrically attached to a conductor as 7, Fig. 7, and the other ribbon 14 is attached to the conductor 6. But before the latter connection is made a glass or ceramic tubular shield 19 is threaded on the conductor wire 6. Then when the wire 6 is connected to the ribbon 55

14 the shield 19 is shifted over toward the near end of the bushing 10, a portion of the insulation of the service wire 6 passing into the shield 19.

5 This hook-up of the service wires 6-7 with the ribbons 14-16 eliminates possibility of shorting the circuit in the handle.

When the hook-up of the heater assembly has been completed the service cord is drawn out through the handle 2 until the cord knot 8 jams 10 in the tapered bore of the handle and at which instant the bushing 10 will be brought into contiguity with the larger end of the handle, wherein it will then be cemented and keyed to complete the tool structure.

15 The muzzle 18 is shown as having a laterally directed scribing nib 18^a for use on various materials without heat, but if a burning tool is desired then the heating unit in the muzzle 18 is energized by electric current.

20 For the purpose of enabling the use of the tool for various kinds of work the muzzle is provided for reception of complementary working elements. In Fig. 2 there is shown a thin bladed element 20 having a chambered hub 21 to screw 25 onto the threads 18^b of the muzzle and thus telescope over the scribing nib. The hub 21 has a drain hole 22 for escape of a finishing wax or fluid onto the blade when this is heated by the energized unit in the muzzle. Fig. 3 illustrates 30 a form of dental wax applying and working element 23, with a chambered and draining hub 24 attachable to the muzzle 18. In Fig. 4 is shown a soldering iron or block 25 attachable to the muzzle 18, as desired. Where necessary to retard flow of the heated wax or fluid in the tool 35 hubs it is obvious that a wick may be introduced with that object.

In Fig. 12 there is disclosed a form of heating unit especially designed for utilization of low 40 voltage current as when derived for a battery as source of supply. In this unit the ribbon-wire 14^x is helically coiled at 27 beyond the end of the tube 13^x and is joined directly to the muzzle 18 to the opposite end of which is attached a con- 45 ductor.

The knot 8 in the wires of the service cord is not only a strain release for the terminals of the heating unit but also is a stop, when engaging the tapered bore of the handle, against the outward pull of the cord in the handle.

5 The terminals of the unit are attached to the wires 6-7 by lapping a terminal of the ribbon 14 on one wire and twisting them together and then clinching them in an applied sheath 14^x, Fig. 7.

10 What is claimed is:

1. An electric hand tool including a heating coil assembly which includes a bushing and a core tube extending from one end thereof, a resistance coil cemented on the tube and in the bushing, coil terminals one of which extends through the tube and the other free outside thereof, service wires connected to the terminals and a refractory tubular shield telescoped on one of the connections and telescoping over the extended core end.

2. An electric hand tool including a heating coil assembly comprising a refractory core tube, a filament coiled on one end thereof, wires of which one extends through the tube and has one end lapped on one end of the tube and bound by one end of the filament and the other wire being attached to the other end of this filament on the tube, a coat of insulating cement covering the coiled filament, a bushing in which the coated coil and tube is cemented and from which the tube extends at each end, and a muzzle fixed on the end of the tube having the filament coil and also fixed in the bushing.

3. An electric heating unit including a working muzzle, a refractory core tube terminating in the muzzle, a wire extending through the tube, a resistance coil, and service connections with and for current through the wire and coil; said tube being cemented in the muzzle; said coil formed of a filament wrapped close on one end of the tube and wide space wrapped medially along the tube so as to form a hot zone entirely within the muzzle.
